UNITED STATES PATENT OFFICE.

LEE S. CHADWICK, OF EAST CLEVELAND, OHIO, ASSIGNOR TO THE CLEVELAND METAL PRODUCTS COMPANY, OF CLEVELAND, OHIO, A CORPORATION OF OHIO.

LATCH.

1,271,131.

Specification of Letters Patent. Patented July 2, 1918.

Application filed September 1, 1914. Serial No. 859,719.

To all whom it may concern:

Be it known that I, LEE S. CHADWICK, a citizen of the United States, residing at East Cleveland, in the county of Cuyahoga and 5 State of Ohio, have invented a certain new and useful Improvement in Latches, of which the following is a full, clear, and exact description, reference being had to the accompanying drawings.

10 This invention relates generally to latches, and particularly to an improved latch that is especially suitable for use in connection with oven doors.

The invention has for its object the provision of a latch that is simple of construction and operation; the provision of a latch that actively maintains a tight joint between the closure and frame in connection with which it is used, the coöperating parts 20 of the latch being under tension when in engagement; the provision of a latch that is very durable and that is comparatively economical of production; and the provision of a latch that is neat and attractive 25 of appearance.

To these ends I provide a latch that is composed, principally, of sheet metal stampings and is constructed, in its preferred form, as illustrated in the accompanying 30 drawings, wherein Figure 1 is a fragmentary front elevation of an oven that is equipped with a latch of my invention; Fig. 2 is a plan, and Fig. 3 a right hand end elevation of the parts shown in Fig. 1; while 35 Fig. 4 is a central horizontal section on the lines 4—4 of Figs. 1 and 3.

In the drawings the wall of the oven is shown at 1 and the door at 2, each of which is formed of a metal shell that is filled with 40 some non-heat conducting material, such as asbestos, in accordance with the usual method of constructing ovens of the class herein shown. The coöperating edges of the wall 1 and the door 2 are of such shape 45 as to form a satisfactory heat retaining joint when the door is closed.

Secured to the door, near its edge, by means of the screws 5, is a base plate 6 having a bracket 7 extending from each of its 50 ends in a plane at right angles to the plane of the base plate, and these brackets extend beyond the edge of the door and have their outer ends turned down to form stops 8. The base plate 6 and brackets 7 are pref-

erably formed of a single piece of sheet 55 metal.

Pivoted between the brackets 7, upon the rivets 10, is the swing member of the latch, said member comprising the end plates 11 through which the rivets 10 pass and which 60 are connected by a bar 12, the end pieces 11 and the bar 12, in the present embodiment of my invention, comprising a single sheet metal stamping. It will be observed, especially from Fig. 4, that the forward edge of 65 the bar 12 is turned back upon itself at 13 in order to give a smooth round surface to the forward edge of the bar, and also for the purpose of strengthening the same. Between the outer ends of the end plates 11 70 there is supported a handle 15 which is preferably formed of a piece of tubing, the ends whereof are contained within the caps 16. The handle and caps are clamped in place by means of the tie rod 17 which has 75 its threaded ends received by the hollow screws 18 which pass through apertures in the end plates 11 and are screwed firmly onto the ends of the tie rod 17. This construction of handle is especially advan- 80 tageous when the grip, comprising the tube 15, is finished in enamel. It is well known that enamel is brittle and that it will chip and scale off if the parts to which it is applied are distorted or strained. Furthermore 85 it is practically impossible to finish the edges of an enameled member smoothly. In the construction above described, the end caps 16 conceal the ends of the enameled tube 15, where the enamel coating is apt to 90 be uneven and unsightly, and these caps may be nickel plated or provided with some similar finish that will not be affected by the clamping action to which the caps are subjected. 95

A leaf spring 20 is secured to the base plate 6, adjacent each of the brackets 7, by a screw 21, and the free end of each spring is turned up under the rear edge of the bar 12. Under the influence of these springs, 100 the swing member of the latch is caused to assume what will be referred to as its normal position, with the edges of the end pieces 11 in engagement with the stops 8.

Secured to the forward edge of the oven 105 wall 1, is the keeper 25 which is formed of resilient material and has a base flange 26 through which the keeper is secured to the

oven wall, by means of the screws 27. The free edge of the keeper 25 is turned toward the door 2, at substantially right angles to its body portion, and is then turned back 5 upon itself as shown at 28. By this arrangement a smooth, rounded edge is given to the keeper, somewhat similar to the rounded edge 13 of the bar 12.

It will be noted that when the swinging 10 member of the latch is in normal position and the door is moved to cause the bar 12 to approach the keeper 25, the advancing side of the bar 12 will be presented to the rounded edge 28 of the keeper in an oblique 15 plane, similar to the action of the inclined nose of the ordinary latch bar, with respect to its keeper. In the act of closing the door, the bar 12 will be permitted to pass the edge of the keeper, principally through the 20 yielding of the springs 20, but partly through the yielding of the keeper 25. After the engaging parts of the latch have passed each other and the forward edge of the bar is contained within the angle between the overturned edge 28 and the body 25 portion of the keeper 25, the springs 20 and the keeper will remain under sufficient tension to cause the edge of the door to be constantly pressed against its seat and thereby insure a perfect joint.

The resiliency of the keeper and springs, however, will permit a slight separation between the coöperating edges of the door and wall, should the pressure within the oven be brought to a sufficient height, by the generation of steam therein, to counteract the effect of the latch. This is clearly an advantage as it provides the necessary ventilation.

40 I have shown herein what I consider, at the present time, to be the preferred embodiment of my invention, although I do not limit myself to such construction except as required by the terms of the annexed claims 45 and the state of the prior art. Furthermore I have referred to the part wherewith the edge of the door or closure coöperates, as the oven wall. This might obviously be the edge of any opening which the door is intended to close, and might better be considered, broadly, a frame. It is thus referred to in the claims.

Having thus described my invention, what I claim is:

55 1. The combination, with a pair of elements comprising one a frame and the other a closure therefor, of a bracket that is carried by one element and having a stop, a latch member pivoted to the bracket and having a keeper engaging portion, means for moving the latch member toward the stop, and a yielding keeper supported by the other element that is arranged to be engaged by the keeper engaging portion of the latch member, said keeper, when engaged, serving

to hold the latch member out of contact with the stop of the bracket.

2. The combination, with a pair of elements comprising one a frame and the other a closure therefor, of a base plate that is carried by one element, a pair of brackets which extend from the base plate and beyond the edge of the closure, one of said brackets having a stop, a latch member which comprises a pair of end plates that are connected by a bar, pivotal connections between the end plates and the aforesaid brackets, a spring for moving the latch member into engagement with the aforesaid stop, and a keeper of resilient material that is supported by the other element in a position to be engaged by the bar of the latch member, said keeper, when engaged, serving to hold the latch member out of contact with the aforesaid stop.

3. The combination, with a frame and a closure therefor, of a base plate that is carried by the closure, a pair of brackets which extend from the base plate and beyond the edge of the closure where they are provided with stops, a latch member which comprises a pair of end plates that are connected by a bar, pivotal connections between the end plates and the aforesaid brackets, springs for moving the latch member so that its end plates engage the aforesaid stops, and a keeper of resilient material that is supported by the frame in a position to be engaged by the bar of the latch member when the closure is in closed position.

4. The combination, with a frame and a closure therefor, of a base plate, a bracket rising from each end thereof and projecting beyond the edge of the closure and having, each, a stop, the brackets and the base plate being formed of a single piece of metal, a latch member that comprises a pair of end plates which are connected by an integral bar one edge whereof is turned over against itself, pivotal connections between the end plates and the aforesaid brackets, a spring that is secured to the base plate and engages the bar of the latch member whereby said latch member is moved to cause its end plates to engage the stops of the brackets, and a keeper that is supported from the frame and has a portion that projects outwardly from the frame and is then turned over in the direction of the closure, the turned over portion being doubled back upon itself and supported in a position to be engaged by the bar of the latch member.

5. The combination, with a frame and a closure therefor, of a base plate carried by the closure and having formed integral therewith at each end a bracket which projects beyond the edge of the closure and is provided with a stop, a latch member comprising a pair of end plates that are connected by an integral bar, pivotal connec-

tions between the end plates of the latch member and the aforesaid brackets, a spring that tends to move the latch member in a direction to cause its end plates to engage 5 the stops of the brackets, the shape and proportions of the parts being such as to cause the bar of the latch member to be in an oblique plane with respect to the direction of movement of the edge of the closure, a 10 keeper that is formed of resilient material and that is supported from the frame and comprising a body portion and a portion that is turned over in the direction of the closure wherewith the bar of the latch member is adapted to engage when the closure 15 is closed.

6. A latch of the character described comprising, in combination, a base plate having a pair of brackets formed integral therewith, 20 a latch member comprising a keeper engaging bar and a pair of end plates formed integral therewith, a handle supported between the end plates, pivotal connections between the end plates and the aforesaid brack-

ets, and a keeper having a bar receiving portion that is adapted to contain the aforesaid bar.

7. A latch of the character described comprising, in combination, a base plate having a pair of brackets formed integral therewith, 30 each bracket being provided with a stop, a latch member comprising a keeper engaging bar and a pair of end plates formed integral therewith, a handle supported between the end plates, pivotal connections between the end plates and the aforesaid brackets, means tending to swing the latch member in a direction to cause its end plates to engage the aforesaid stops, and a resilient keeper having a bar receiving portion 35 that is adapted to contain the aforesaid bar.

In testimony whereof, I hereunto affix my signature in the presence of two witnesses.

LEE S. CHADWICK.
